J. M. LEACH

SHIPPING CASE

Filed July 7, 1922

UNITED STATES PATENT OFFICE.

JAMES M. LEACH, OF SMITHTON, PENNSYLVANIA.

SHIPPING CASE.

Application filed July 7, 1922. Serial No. 573,358.

To all whom it may concern:

Be it known that I, JAMES M. LEACH, a citizen of the United States, residing at Smithton, in the county of Westmoreland and State of Pennsylvania, have invented certain new and useful Improvements in Shipping Cases, of which the following is a specification.

My invention relates to shipping cases, more particularly to metallic collapsible shipping cases, and has for its general object to provide a simple and efficient crate which may be expeditiously and conveniently set up for shipping or folded in a most compact form for reshipping. And to these ends the invention consists in providing the crate with a plurality of hingedly connected sections so connected and arranged that the crate can be securely locked in either the set-up or knocked-down position.

With the foregoing and other objects in view the invention consists of the novel construction, combination and arrangement of parts as hereinafter more specifically described and illustrated in the accompanying drawing, wherein is shown an embodiment of the invention, but it is to be understood that changes, variations and modifications can be resorted to which come within the scope of the claims hereunto appended.

In the drawing forming a portion of this specification and wherein like numerals of reference designate corresponding parts throughout the several views:—

Figure 1 is a perspective view of the shipping case in its set-up position.

Figure 2 is a side view showing the case in the knocked down and folded position ready for shipment.

Figure 3 is a fragmentary front view of the case illustrating the locking elements therefor.

Figure 4 is a fragmentary sectional view showing the pin connection of the cover with one of the side walls of the case.

Figure 5 is a fragmentary perspective view illustrating a modified form of connecting element for securing the side and end walls.

Referring in detail to the drawings the shipping case comprises side walls 1 and 2, end walls 3 and 4, cover 5 and bottom 6. The side edges of the bottom 6 are formed with upstanding flanges 7 and 8, respectively. The side wall 1 has its lower edge

hinged, as at 9, to the upper edge of the flange 7, and the lower edge of the other side wall 2 is hinged, as at 10, to the upper edge of the flange 8. The end wall 3 is hinged, as at 11, to an end edge of the bottom 6 and the end wall 4 is hinged to the other end edge of the bottom 6.

The hinged connections of the end walls and side walls with the bottom 6 are preferably constructed by providing adjacent hinged edges with integrally formed interengaging tubular beads through which suitable pintles 12 are inserted. Any other type of connecting hinge may be successfully employed, it only being necessary that such hinged connections permit of the side walls 1 and 2 to be folded toward each other, and the end walls 3 and 4 to fold inwardly toward each other.

Each of the vertical edges of the side walls 1 and 2 is formed with an inwardly disposed flange 13 which is adapted to overlap the adjacent vertical edge of respective end walls 3 and 4, when the case is in the set up position as illustrated in Figure 1. The flanges 13 also serve to re-inforce the structure and prevent liability of buckling of the side and end walls if cases with heavy contents, are stacked upon each other or under other objects. If desired, the vertical edges of the end walls 3 and 4 may be rolled inwardly or bent upon itself to provide additional re-inforcement for the purposes above stated.

The material from which the case is made is preferably flat sheet metal, although other materials and other forms of sheet metal may be used if desired.

The cover 5 is formed with a depending flange 14 which extends along the entire length of each of the four edges of the cover 5, and is adapted to overlap the top edges of the side and end walls when the case is in the set up position.

Pivottally connected, as at 15, adjacent to each of the upper corners of the end walls 3 and 4, is a hook member 16, which engages the respective corners of the side walls 1 and 2 and secures the latter with the end walls 3 and 4 to hold the case in the set up position. Each of the corners of the side walls 1 and 2 is provided with a recess 17 for the reception of the hook member 16, so that the upper portion of the latter when engaged therein will be flush with the top edges of the side and end walls. When the

cover 5 is in the closed position the under surface thereof will be in contact with the upper portions of the hook members 16 and lock same against accidental release.

5 That portion of the cover flange 14, which overlaps the top edge of the end wall 1, carries a fixed pair of spaced pins 18. The upper edge of the side wall 1 is provided with a pair of corresponding apertures 19, 10 adapted for the reception of the pins 18 for securing the cover 5 to the side wall 1.

Secured, as at 19', at the central forward portion of the cover 5, is a hasp 20, including a short section 21 hinged, as at 22, at 15 the extreme edge of the cover 5, and an elongated section 23 hinged, as at 24, to the short section 21. The section 23 is formed with a pair of aligned slots 25 and 26, the former adapted for the passage of the 20 staple 27 which is fixedly carried on the outer face of the side wall 2 adjacent to its upper end, and the latter for the purpose hereinafter described. A lock or bolt (not shown) is adapted to engage the staple 27 to lock the cover in the closed position in 25 the usual manner.

The bottom flange 8 is formed with a pair of apertures 28 adapted for the reception of the pins 18, carried by the cover flange 14, 30 when the case is in the collapsed position, in a manner now to be described.

The modification in Figure 5 illustrates a side wall 1, having an inwardly stamped portion 29, forming an aperture 30 adapted 35 for the reception of the hook member 16 for securing the said side wall with the end wall. In the preferred form the hook member simply overlaps the side wall in the recess 17.

40 Assuming that all parts of the case are in the set up position as shown in Figure 1 of the drawing, the case is folded by releasing the hasp 20 from the staple 27 and shifting the cover 5 to disengage the pins 18 from the apertures 19 in the upper end of the side wall 1. The cover 5 may now be entirely removed, permitting of the hook members 16 to be shifted to release the respective side walls 1 and 2.

50 The end members 3 and 4 are folded inwardly upon the bottom 6, one of said members overlapping the other. The collapsed end members 3 and 4 are disposed intermediate of the bottom flanges 7 and 8, which 55 are approximately commensurate in height with the combined folded end walls 3 and 4.

The side wall 1 being hingedly connected to the upper edge of the bottom flange 7 the said side wall is folded inwardly to overlap the end walls 3 and 4. The other side

wall 2, carrying the staple 27, is folded inwardly to overlap the end wall 1, the flanges 13 of the side wall 2 being disposed and arranged to overlap the flanges 13 of the side wall 1.

65

The cover 5 is now positioned over the bottom 6 by inserting the pins 18 into the apertures 28 in the bottom flange 8, and securing the hasp 20 to the staple 27 which latter will extend through the slot 26 in the 70 elongated portion 23 of the hasp.

75 In this manner the case may be compactly knocked down to provide a flat package readily and conveniently stacked and stored for transportation or for any other purposes desired.

What I claim is:—

1. A collapsible case comprising a cover provided with a hasp and a pair of pins, a bottom having each of its side edges formed with an upstanding flange, a side wall hingedly connected to each of said flanges, an end wall hinged to each of the end edges of said bottom, hook members pivotally carried by said end walls and adapted to engage said side walls for securing the latter with the end walls in the vertical position, one of said side walls formed with apertures for the reception of the pins carried by said cover, and the other of said side walls having a staple mounted thereon adapted to be engaged by said hasp for locking the said cover in the closed position.

85

90 2. In a collapsible shipping case, the combination of a bottom having each of its side edges formed with an upstanding flange, a side wall hinged to each of said flanges, one of said flanges formed with a pair of apertures, an end wall hinged to each of the end edges of said bottom, the upper corners of 95 said side walls being recessed, a hook member pivotally mounted on the inner face of said end walls adjacent to each upper corner thereof and adapted to engage in the recesses of the side walls for securing the latter and the end walls in the vertical position a flanged cover provided with a hasp and with a pair of pins fixed in the flange thereof, one of said side walls formed with 100 apertures adapted for the reception of said pins, the other of said side walls provided with a staple adapted to be engaged by said hasp for locking said cover when the case is in the set up position, said pins further 105 adapted to engage in the apertures formed in the bottom flange when the case is in the folded position, substantially as described.
